UNITED STATES PATENT OFFICE.

RAYMOND F. HOLWAY, OF OAKLAND, CALIFORNIA.

CONTAINER AND PROTECTOR FOR ROLL-ROOFING.

1,365,403.

Specification of Letters Patent. Patented Jan. 11, 1921.

Application filed April 1, 1918. Serial No. 226,080.

To all whom it may concern:

Be it known that I, RAYMOND F. HOLWAY, a citizen of the United States, residing at Oakland, in the county of Alameda and State of California, have invented new and useful Improvements in Containers and Protectors for Roll-Roofing, of which the following is a specification.

This invention relates to a container and protector for roll roofing which is composed of sheets of resistant, waterproof, flexible material, adapted to be laid upon a roof with the meeting edges of the sheets connected together to form a continuous protective covering. These sheets are made of an approved length and width and are rolled for transportation and delivery. In order to protect the edges of the rolls from being bruised and damaged, and to inclose in each roll the means for securing and connecting them together in a complete sheet, an inclosing tube is inserted into the interior of each roll, having protective flanges at the ends and separating flanged disks inserted 25 to form pockets in which the cement containers, nails, and other requisites may be separately contained and protected.

The invention consists in details of construction which will be more fully explained 30 by reference to the accompanying drawings, in which—

Figure 1 is a longitudinal section of a roll and container.

Fig. 2 is an exterior view.

Fig. 3 is a section showing the flanged interior disks.

As shown in the drawings, A is a roll of material suitable for roofing purposes, and having a central, tubular space adapted to 40 contain the herein described structure and the necessary accessories, so that when it reaches the place of use, it contains everything necessary for assembling any number of sheets to complete a roof.

In order to protect the rolls, and especially the ends which, when unrolled, comprise the meeting edges of the sheets, flanges 45 are made to cover these ends. These flanges are secured to the ends of tubes 3 and 4, which fit within the roll and may telescope together so as to adjust themselves to the length of the roll and bring the protective flanges 2 into contact with the roll ends. The outer ends of the tubes are 50 turned outwardly or otherwise formed with disk flanges 2. A hollow cup-shaped cushion

member 5 extends from the disk flange 5^a into the end of the contiguous tube and forms a cushion and seat against which a can of sheet uniting cement rests. Against the 60 opposite end of this can rests the bottom 7 of the cup-shaped receptacle 7^a and opposed to this cup is another cup 8^a; the edges of the two meeting and completing the receptacle for nails or other fastenings. 65 Another cup-shaped member 9 is fitted into the tube with its bottom contacting with the bottom 8, and its open opposite end facing or in contact with the inner end of the opposite tube, so that the telescoping adjustment of the tubes to fit the length of the roll may position and retain the receptacles and prevent undue movement during transportation. The parts may be retained in final adjustment by any suitable adhesive 70 cement and the ends may be further protected by caps 11.

By thus constructing and assembling the parts everything necessary is compactly contained and protected in readiness for immediate use and the cost is greatly reduced. 80 It should be understood that the container may be placed in either end of the device.

Having thus described my invention, what I claim and desire to secure by Letters 85 Patent is—

1. A roof roll container and protector comprising telescopic tubes adjustable within the roll, a flange formed at the outer end of one of the tubes for engagement with an 90 end of the roll, means carried by the other tube for engagement with the opposite end of said roll, and retaining means on each end of the roll to abut and protect the ends 95 of the roll.

2. A roof roll container and protector comprising telescopic tubes adjustable within the roll, a flange formed at the outer end of one of the tubes for engagement with an end of the roll, means carried by the other tube for engagement with the opposite end of said roll, retaining means on each end of the roll to abut and protect the ends of the roll, and a disk abutting said flange and 100 inclosed by the retaining means.

3. A carrier and protector for roofing rolls consisting of tubular cylinders, one adapted to telescope within the other, a flange at the outer end of the larger cylinder to contact with and protect the contiguous end of the roll, a hollow cup with a cushion bottom extending into the smaller 110

cylinder and having a flange at its outer end fitting against the outer end of the smaller cylinder, and a disk for each end of said container, one abutting the flange of the cap 5 the cap and the other the flange of the cylinder.

4. A carrier and protector for roofing rolls consisting of tubular cylinders, one adapted to telescope within the other, a 10 flange at the outer end of the larger cylinder to contact with and protect the contiguous end of the roll, a hollow cup with a cushion bottom extending into the smaller cylinder and having a flange at its outer end

fitting against the outer end of the smaller cylinder, a disk for each end of said container, one abutting the flange of the cap and the other the flange of the cylinder, and elastic bottomed containers abutting each other within the cylinders. 15

In testimony whereof I have hereunto set my hand in the presence of two subscribing witnesses. 20

RAYMOND F. HOLWAY.
